United States Patent Office

Des. 198,000
Patented Apr. 14, 1964

198,800

REFRIGERATOR

Joel D. Fogel, 5400 Eadom St., and Daniel J. Mangini,
2824 Nature Road, both of Philadelphia, Pa.

Filed July 16, 1962, Ser. No. 71,001

Term of patent 7 years

(Cl. D67—3)

FIG. 1 is a perspective view of a refrigerator showing our new design.

FIG. 2 is a top plan view thereof.

FIG. 3 is a right side elevational view thereof.

FIG. 4 is a rear elevational view thereof.

FIG. 5 is an enlarged fragmentary perspective view showing upper left front corner of door and upper portion of handle.

FIG. 6 is a left side elevational view thereof.

FIG. 7 is an enlarged fragmentary perspective view showing upper left front corner of the refrigerator.

The drawing is stippled to show contrast.

The dominant features of our design reside in the portions shown in full lines.

We claim:

The ornamental design for a refrigerator, as shown and described.
